UNITED STATES PATENT OFFICE

160,321

ALPHABET FOR FORMING MONOGRAMS
OR SIMILAR ARTICLE

George A. Ingleby, Edgewood, R. I., assignor to
The Hadley Company, Inc., Providence, R. I.,
a corporation of Rhode Island

Application July 29, 1949, Serial No. 4,192

Term of patent 14 years

(Cl. D64—12)

To all whom it may concern:

Be it known that I, George A. Ingleby, a citizen of the United States of America, residing in Edgewood, county of Providence, and State of Rhode Island, have invented a new, original, and ornamental Design for an Alphabet for Forming Monograms or Similar Article, of which the following is a specification, reference being had to the accompanying drawing, forming a part thereof.

Fig. 1 is a plan view of an alphabet for forming monograms or similar article, showing my new design;

Fig. 2 is an end elevation on line 2—2 of the letter "A" of Fig. 1; and

Fig. 3 is a side elevation on line 3—3 of the letter "B" of Fig. 1.

I claim:

The ornamental design for an alphabet for forming monograms or similar article, substantially as shown.

GEORGE A. INGLEBY.
